Primary Examiner — John Windmuller*Assistant Examiner* — Steven Czyz(74) Attorney, Agent, or Firm — John B. Edel; Edel Patents LLCCLAIM

The ornamental design for a moistening thimble, as shown and described.

DESCRIPTION

FIG. 1 is a front perspective view of a moistening thimble showing my new design;

FIG. 2 is a front elevation view thereof;

FIG. 3 is a rear elevation view thereof;

FIG. 4 is a left side elevation view, with the right side being a mirror image thereof;

FIG. 5 is a top plan view thereof; and,

FIG. 6 is a bottom plan view thereof.

The right side elevation view, not shown, is a mirror image of the left side elevation view.

The broken lines depict portions of the article that form no part of the claimed design.

1 Claim, 3 Drawing Sheets(56)
